UNITED STATES PATENT OFFICE.

THOMAS W. SMITH, OF DELPHOS, OHIO.

FENCE-POST.

1,107,858.

Specification of Letters Patent. Patented Aug. 18, 1914.

Application filed October 4, 1913. Serial No. 793,426.

To all whom it may concern:

Be it known that I, THOMAS W. SMITH, a citizen of the United States of America, residing at Delphos, in the county of Allen 5 and State of Ohio, have invented certain new and useful Improvements in Fence-Posts, of which the following is a specification, reference being had therein to the accompanying drawing.

10 This invention relates to fence posts and has for its object the production of a simple and efficient means for attaching the wires to the post in such a manner as to prevent the accidental releasing of the wires from 15 the post.

Another object of this invention is the production of a simple means for allowing the wires of a fence to be quickly attached to the post.

20 With these and other objects in view, this invention consists of certain novel combinations, constructions and arrangements of parts as will be hereinafter fully described and claimed.

25 In the drawing: Figure 1 is a perspective view of the post in an assembled position. Fig. 2 is a side elevation of the post showing the wires in transverse section. Fig. 3 is a central vertical section through the post. 30 Fig. 4 is a section taken on line 4—4 of Fig. 2. Fig. 5 is a detailed perspective of the upper end of the main body portion of the post. Fig. 6 is a detailed perspective of the outer portion of the auxiliary or locking 35 portion of the post.

By referring to the drawing it will be seen that 1 designates the body of the post which is substantially semi-circular in cross section and tapers toward the upper end 40 thereof. The substantially semi-circular body portion of the post is provided with a pair of slightly converging flange portions 2, which flange portions are provided with substantially U-shaped notches 3, one end of 45 the U-shaped notch extending to the outer edge of the flange 2 and the other end terminating short of the outer edge of the flange 2, thereby producing an inwardly extending lip 4 upon the flanges 2 for the purpose of constituting an overhanging finger 50 or lip to retain the wire strands 5 in their correct position. It should, of course, be understood that as many of these notches 3 can be used as is desired to be used with the 55 present device.

A locking plate 6 which is substantially

U-shaped in cross section fits over the flanges 2 of the body 1 and this locking plate 6 is provided with substantially L-shaped notches 7 which notches are provided with inwardly 60 extending knob portions 8 for reducing the width of the notch 7 at the angle portion thereof. The inner end of the notch 7 is rounded, as indicated at 9 for the purpose of constituting a pocket for receiving the wire 65 strands 5. It should be understood that by having the notch 7 substantially L-shaped, this construction will produce a depending lip 10, and owing to the knob portion 8 being formed thereon, it will be seen that 70 this depending lip 10 may have an outward swinging movement under undue pressure when a wire strand is passed into the pocket portion 9. After the wire strand is placed in the pocket portion 9, the lip 10 75 will assume its normal position and constitute a locking means for retaining the wire strand in its correct position.

In assembling the posts the wire strands are first placed in the notches 3 having the 80 wire strand fitting under the inwardly extending lip or finger 4. The locking plate is then placed over the flanges 2 and is so forced upon the flanges 2 as to cause the wires 5 to be inserted in the notches 7. 85 By forcing the locking plate 6 downwardly when the wires are in the position shown in Fig. 2, the lips 10 will be forced slightly outwardly and the wires 5 will then be seated in the pocket portion at 90 the upper end of the notches 7 and thereby constituting an efficient means for holding the wires in their correct assembled position. The vertical strands or wires 11 are then connected or bound to the horizontal 95 strands 5 by means of a wire or cord 14 of any suitable construction.

From the foregoing description it will be seen that a very simple and efficient means has been produced for holding the wires in 100 firm engagement with the post and that the lip 10 of the locking plate 6 will resist the lateral movement of the strands relative to the post 1 and the lip 4 of the body portion of the post 1 will constitute means for resisting the outward movement of the wire strands 5. It should be understood that the bracing device may be made of sheet metal and may, therefore, be very cheaply manufactured. It should be further understood 105 that since the several sections of the fence post are provided with the interlocking slots,

the transversely extending wires 5 which pass through the slots formed in the post may be firmly held against movement upon the post, in view of the fact that the lips 8 of the section 6 of the post will constitute a lock for holding the wires in a set position and prevent the vertical movement of the section 6 of the post upon the body or section 1 thereof. Furthermore, the wires may 10 be easily inserted or placed in engagement with the post owing to the manner of forming the several slots formed in the respective sections of the post, and at the same time the sections may be so operated as to readily 15 release the wires from the post.

What is claimed, is:

A fence post comprising a body, provided with flanges, said flanges provided with substantially U-shaped notches, one end of 20 said U-shaped notches communicating with the outer edge of said flanges and the other

end of said U-shaped notches terminating short of the outer edge of said flanges thereby producing an inwardly extending tongue, a locking plate substantially U-shaped in 25 cross section provided with a plurality of angle notches, thereby producing a plurality of depending lips, knob portions formed upon the inner edges of said lips and registering with said angle notches at the angle 30 portion thereof, said angle notches fitting over said U-shaped notches and adapted to hold a wire strand of a fence in the upper end of said angle notches and under said inwardly projecting tongue formed upon said 35 flanges of said body.

In testimony whereof I hereunto affix my signature in presence of two witnesses.

THOMAS W. SMITH.
